CLAIM

The ornamental design for a cap, as shown and described.

DESCRIPTION

FIG. 1 is a front, right and top perspective view of a first embodiment of a cap showing our new design;
FIG. 2 is a front elevational view of the cap of FIG. 1;
FIG. 3 is a back elevational view of the cap of FIG. 1;
FIG. 4 is a left side elevational view of the cap of FIG. 1;
FIG. 5 is a right side elevational view of the cap of FIG. 1;
FIG. 6 is a top plan view of the cap of FIG. 1;
FIG. 7 is a front, right and top perspective view of a second embodiment of a cap showing our new design;
FIG. 8 is a front elevational view of the cap of FIG. 7;
FIG. 9 is a back elevational view of the cap of FIG. 7;
FIG. 10 is a left side elevational view of the cap of FIG. 7;
FIG. 11 is a right side elevational view of the cap of FIG. 7;
and,
FIG. 12 is a top plan view of the cap of FIG. 7.

The dotted lines are included for the purpose of illustrating portions of the cap that form no part of the claimed design, with the dot-dash lines being representative of boundary between claimed and unclaimed subject matter.
